CLAIM

The ornamental design for a combined phone handset and base for teleconference, as shown and described.

DESCRIPTION

FIG. 1 is a front perspective view of a combined phone handset and base showing our new design;

FIG. 2 is a rear perspective view of the combined phone handset and base of FIG. 1;

FIG. 3 is a front view of the combined phone handset and base of FIG. 1;

FIG. 4 is a rear view of the combined phone handset and base of FIG. 1;

FIG. 5 is a left side view of the combined phone handset and base of FIG. 1;

FIG. 6 is a right side view of the combined phone handset and base of FIG. 1;

FIG. 7 is a top view of the combined phone handset and base of FIG. 1;

FIG. 8 is a bottom view of the combined phone handset and base of FIG. 1;

FIG. 9 is a front perspective view of the base only;

FIG. 10 is a front view of the base of FIG. 9;

FIG. 11 is a left view of the base of FIG. 9;

FIG. 12 is a top view of the phone handset only;

FIG. 13 is a bottom view of the phone handset of FIG. 12;

FIG. 14 is a left side view of the phone handset of FIG. 12; and,

FIG. 15 is a front perspective view of the combined phone handset and base with the phone handset removed from the base.

The broken lines in FIG. 8 that show the outermost periphery of non-claimed features represent the boundaries of the claimed design. All other broken lines are directed to environment and are for illustrative purposes only. The broken lines, and unshaded regions defined by broken lines, form no part of the claimed design.
